FIG. 4

FIG. 5

FIGURE 1 is a front perspective view of a typewriter showing our new design;

FIGURE 2 is a top plan view to a reduced scale thereof;

FIGURE 3 is a left side elevation view of FIGURE 2;

FIGURE 4 is a rear perspective view of the typewriter; and

FIGURE 5 is a view similar to FIGURE 4 but showing the hinged, rear storage compartment in open position.

The keys are fragmentarily depicted in FIGURES 1 and 2 and extend across the keyboard as indicated by the dot-dash lines.

We claim:

The ornamental design for a typewriter, substantially as shown and described.
